UNITED STATES PATENT OFFICE.

FRANK J. FOVEAUX, OF ALAMEDA, CALIFORNIA.

FURNACE.

SPECIFICATION forming part of Letters Patent No. 662,926, dated December 4, 1900.

Application filed May 5, 1899. Renewed July 16, 1900. Serial No. 23,824. (No model.)

To all whom it may concern:

Be it known that I, FRANK J. FOVEAUX, a citizen of the United States, residing at Alameda, in the county of Alameda and State of California, have invented certain new and useful Improvements in Furnaces; and I do hereby declare the following to be a full, clear, and exact description of said invention, such as will enable others skilled in the art to which it most nearly appertains to make, use, and practice the same.

This invention relates to improvements in furnaces; and it consists in the novel arrangement and construction of the parts, as hereinafter set forth.

In the drawings, Figure 1 is a side elevation of a boiler and furnace having this invention applied thereto. Fig. 2 is a plan view of the fire-box of the furnace, showing the arrangement of the air-distributing pipes. Fig. 3 is an end elevation, diagrammatic in form, to show the lines of intersection of the air as ejected from the air-pipes. Fig. 4 is an enlarged detail view, in side elevation, showing the forward end of the air-distributors. Fig. 5 is a sectional view of the same, taken on the lines X X, the view being directed, as shown, by the arrow in Fig. 4. Fig. 6 is an enlarged detail view of the rear end of the air-distributing pipes. Fig. 7 is an end elevation of the view shown in Fig. 6.

One object which the present invention has in view is to provide a construction whereby air may be introduced into the fire-box of a furnace above the bed of the fire to spread the injected air across the entire surface of the fire-box and across the line of draft of the furnace to disperse the gas volumes and to admix therewith the oxygen contained in the injected air to produce a more complete and added combustion.

A further object is to produce a construction that may be applied to the existing furnaces without necessitating a change in construction of the present fire-box or necessitate the diminution of its surface.

With these objects in view the invention consists in extending across the surface of the fire-box and across the line of draft of the furnace pipes to be used in conjunction with an air-blast, the pipes being perforated on the under side to eject streams of air radially

from and below the center of the pipes, the said pipes being distributed across the surface of the fire-box and supported by the 55 walls thereof.

It further consists in the construction and arrangement of the pipes connected with the boiler and clustered about the said air-pipes and inclined to permit the water contained 60 within them to circulate for the purpose of protecting the air-pipes from the heat of the furnace while utilizing the heat for steam production.

To facilitate the description of the invention with reference to the drawings, I will use the letter A to designate the fire-box of a furnace of any desired construction. The letter B will be used to indicate the heating-tubes of the ordinary boiler construction, and 70 the letter C the boiler. All of these parts may be any of the known and desired constructions in which the fire-box is provided with feeding-doors, grate-bars, and passage below the same for the introduction of an air-draft. 75

The fire-box is provided with a front wall A' and rear wall A². In the style of construction shown in the drawings the rear wall A² is utilized for the additional purpose of supporting the group of heating-tubes. These heating-tubes are provided at either end with what are styled "lakes" B' B', from which the water contained in the tubes is received from the one at the lower or depressed end of the 85 tubes and delivered into the one at the upper end, from whence it passes into the boiler C.

Between the front wall A' and the rear wall A² are suspended the air-distributing pipes constructed in accordance with this invention. 90 The distributing or air pipes D are long enough to extend across the space between the front wall A' and rear wall A² of the fire-box to be supported thereon. The inner or rear end is provided with a solid cap D², while 95 the forward end is extended through a hollow collar and is suitably connected with the main supply-pipe E. The pipe D is provided with a number of perforations D' on its undersurface. These perforations are so placed 100 in the pipe that radial lines drawn through the center of the pipe and the center of the extreme perforations would extend at an angle to the perpendicular and the grate-bars.

These extreme lines of the perforations, together with the intermediate perforations, produce when the invention is being operated a spray of atmospheric air striking down upon and spreading over the surface of the fire-bed. The main pipe E is connected with any suitable air-propelling device. The number of the air-pipes D used in a furnace is dependent upon the width of the fire-box and 10 the height at which the pipes D are placed above the fire-bed. It is designed that the radial lines drawn through the center of each pipe and the extreme perforations D' should in the adjacent pipes intersect above the 15 fire-bed. Whether there are one or many of these perforated air-pipes used, however, does not necessitate the altering of the construction of the fire-box of the furnace further than to form the pockets or receptacles 20 in the walls A' A² for the ends of the pipe to rest therein.

When the pipes D are connected to the main pipe E, the operation of the invention is as follows: When the fire is started and 25 under way, the draft through the stack or other forms of draft being established, the air is admitted into the main pipe E, which, as shown in the drawings, extends across the front of the furnace and by it is conducted into the distributing-pipes D under 30 greater or less pressure, which has the effect of forcing it through the perforations D' with greater or less force to produce small streams of air striking downward and slightly diffused over the bed of the fire. Under ordinary circumstances, and particularly when burning bituminous coal, there is liberated an amount of heavy monoxid gas, which 35 passes away so rapidly as to avoid being consumed in which avoidance it is aided by its tendency to hold together and also by the fact of its non-combustibility until properly admixed with oxygen. The effect of driving this air by the diffused streams spoken of 40 onto the fire-bed is that besides injecting an amount of oxygen-containing atmosphere into this gas, and thereby rendering it readily combustible, the gas forms are broken up and dispersed, so that when in full operation 45 the total gases of the kind specified are thrown back within the influence of the combustion and there consumed.

It is to prevent the overheating of the air-pipes D that I have provided the cluster of 50 water-circulating pipes F. These are arranged about the under side of the pipe D, spaces being left between the pipes E for the passage of the air from the perforations. The pipes F rest near or against the pipe D. 55 They extend between two hollow chambers F' and F². The chamber F', besides receiving the pipes F, also receives and supports the upper and forward end of the pipe D, as shown particularly in Fig. 4 of the drawings. 60 This chamber F' is connected by a suitable pipe F³ to the upper lake of the boiler-heating tubes. The hollow-chamber F² is semi-

circular in form, as shown in Figs. 6 and 7, and is connected, by means of suitable pipes F⁴, to the cylinder or drum F⁵, which is connected 70 to the lower of the two lakes forming part of the heating-tubes for the boiler. By means of these connections with the upper and lower lakes of the boiler-heating tubes the pipes F are maintained filled with water. They are 75 inclined to the same angle as are the heating-tubes B in order that an even circulation of water may be maintained in the pipes F when the water contained therein is heated. In this manner the heat, which might otherwise 80 destroy the distributing-pipes D, is carried away and its surface is maintained relatively cool. The pipes F are suitably mounted in the hollow chambers F' F² in the form of clusters, and the construction is independently completed by the tie-rods F⁶, which extend through certain of the pipes F and 85 through the hollow chambers, to be secured and tightened as desired. The chambers F' F² are provided with screw-plugs F⁷ of the 90 usual construction, in line with the pipes F, whereby the said pipes are cleaned.

While I have here described the construction as embodying an air-blast and the main supply-pipe used in conjunction therewith, I 95 do not wish to limit myself to such construction, for very excellent effects may be obtained by merely opening the outer ends of the pipes D and permitting the air to flow through them into the fire-box. This is particularly true where a forced air-draft is used 100 in firing, which causes a partial vacuum in the fire-space, to fill which the air rushes through the pipes D and the perforations therein. This construction, together with 105 regulating-dampers, I wish to be understood as claiming.

It will now be observed that with a construction such as described the apparatus may be applied to any of the well-known constructions of furnaces of any width without necessitating the alteration of the construction of the fire-box as has heretofore existed. All that is required in applying the present invention is merely to use a large enough 115 number of air-pipes D, so that they will not become separated too far.

Having thus described this invention, it is claimed—

1. In a furnace, a front and rear hollow 120 chamber, said front chamber having an opening therethrough, an air-pipe extending through said opening and above the grate-bars and having its under surface provided with perforations, a cluster of water-tubes 125 about the under side of said pipe and opening into said chambers, said tubes being separated on lines corresponding with the lines of the perforations in the air-pipe to permit the egress of the air, and connecting water-channels between the said chambers and the water-space of the boiler; substantially as described.

2. In a furnace, a series of water-tubes,

front and rear lakes into which said tubes open, a front and rear hollow chamber, said front chamber having an opening therethrough, an air-pipe extending through said 5 opening and above the grate-bars and having its under surface provided with perforations, a cluster of water-tubes about the under side of said pipe and opening into said chambers, said tubes being separated on lines corresponding with the lines of the perforations

in the air-pipe to permit the egress of the air, and connecting water-channels between the said chambers and the said corresponding lakes; substantially as described.

In testimony whereof I have hereunto set 15 my hand this 24th day of April, 1899.

FRANK J. FOVEAUX.
